(57) **CLAIM**

The ornamental design for a garbage sack, as shown and described.

DESCRIPTION

FIG. 1 is a front perspective view of a garbage sack in the open position showing my new design;

FIG. 2 is a rear perspective view of a garbage sack in the open position;

FIG. 3 is a bottom perspective view of a garbage sack in the open position;

FIG. 4 is a right side elevational view of a garbage sack, with the left side elevational view being a mirror image thereto; and,

FIG. 5 is a top plan view of a garbage sack, in a closed or compressed position. The broken lines on the garbage sack depict folds.

1 Claim, 5 Drawing Sheets

Matter enclosed in heavy brackets [ ] appears in the original patent, but forms no part of this reissue; matter printed in italics indicates the additions made by reissue.
